(57) **CLAIM**

The ornamental design for a shower head, as shown and described.

DESCRIPTION

FIG. 1 is a bottom plan view of a shower head showing my new design;

FIG. 2 is a top, rear, right perspective view thereof;

FIG. 3 is a rear elevational view thereof;

FIG. 4 is a right-side elevational view thereof, the left-side elevational view being a mirror image of the right-side elevational view;

FIG. 5 is a front elevational view thereof;

FIG. 6 is a top plan view thereof; and,

FIG. 7 is a bottom, rear, right perspective view thereof. The broken lines in FIGS. 2-6 represent portions of a shower head and form no part of the claimed design.

1 Claim, 7 Drawing Sheets
